Inventor:
John I. McDonald
By: W. R. Handic *Atty.*

UNITED STATES PATENT OFFICE.

JOHN I. McDONALD, OF ST. JOSEPH, MISSOURI.

COMBINATION SAFETY AND PENCIL POCKET.

Application filed March 27, 1926. Serial No. 97,996.

This invention relates to those pockets for garments, particularly for overalls, which are commonly known as "safety" pockets, the purpose being to provide for holding a 5 watch, or other article, in such manner that the same will not fall out of the pocket when the wearer assumes a stooping posture.

The object of my invention is to provide an improved pocket, particularly for overalls, which will embody a safety pocket and a scabbard pocket combined in an improved manner and comprising the outer wall and the partition of the main pocket, whereby the garment is equipped with a main pocket, 10 for ordinary uses, a safety pocket, and a scabbard pocket, while, at the same time, making provision in the scabbard pocket for the accommodation of pencils of different lengths and for their retention. 15

20 A practical embodiment of the invention comprises a main pocket whose front consists of an outer wall and an inner partition stitched together in such manner that a safety pocket is provided between the outer wall and the partition and a scabbard pocket with button hole openings or entrances is provided at one side of the safety pocket, without, however, narrowing the normal width of the main pocket which is 25 open at the top.

An embodiment of the invention which has been found to be of practical and commercial value is hereinafter described and is disclosed in the accompanying drawings, 30 in which:

Figure 1 is a perspective view showing the pocket applied to the bib of overalls; and

Figure 2 is an enlarged detail view of the 40 same, parts being broken away.

Assuming that the present improvements are applied to overalls, the bib of the overalls appears at 1. The combination pocket embodying my invention has an outer wall 45 or front 2 and an inner wall, lining, or partition 3 stitched together around their edges. The mouth 4 of the main pocket is neither obstructed nor shortened by reason of the provision of the safety pocket and the scabbard pocket now to be described, on the outer wall and partition aforesaid.

The front 2 and partition 3 are stitched

to the bib at 5, providing a pocket whose mouth is shown at 4 in which may be placed any desired articles. Vertical stitching 55 defines a scabbard pocket 7. The safety pocket which is provided between the front 2 and partition 3 is shown at 8, the mouth thereof appearing at 9.

The scabbard pocket 7, unlike the pockets 60 of that character heretofore known to the art, is formed wholly of the front 2 and partition 3. Consequently, the mouth 4 of the main pocket is neither shortened nor obstructed by the provision of the scabbard 65 pocket.

The back of the scabbard pocket 7 is formed by the partition 3, and the front thereof by the front 2. The scabbard pocket is provided with a plurality of, say two, 70 openings or entrances 10 and 11, arranged at different heights. For instance, the upper entrance 10 may be at the extreme top of the pocket 7 and the other entrance 11 about midway the height thereof. These entrances afford means to permit the insertion 75 of pencils of different lengths.

It will be observed that the pencils are suitably retained in the scabbard pocket without in any manner interfering with the 80 introduction or removal of a watch from the safety pocket 8 through the mouth 9 thereof or interfering with the use of the mouth 4 for the introduction of articles into the main pocket or their removal therefrom. 85

I claim:

A combination pocket comprising a front and a partition stitched together around their edges and also stitched to the garment thereat except at the top, said partition being left free at its top to constitute a mouth between the partition and the garment, the front and partition being provided therebetween with a supplemental safety pocket having a mouth arranged in a general upright position, the front and partition being connected together by upright lines of stitching to provide a scabbard pocket, said scabbard pocket being located in front of the main pocket and provided with entrance 90 openings at different heights thereof in the aforesaid front. 95

In witness whereof I affix my signature.
JOHN I. McDONALD.
